3,005,931 ION GUN

Raphael A. Dandl, Oak Ridge, Tenn., assignor to the United States of America as represented by the United States Atomic Energy Commission

Filed Mar. 29, 1960, Ser. No. 18,461
6 Claims. (Cl. 315—111)

This invention relates to apparatus for the production of an electrically neutral ionized plasma. Such a plasma may be used in a variety of accelerators, mass spectrometers, high temperature chemical reactors, and other electrical devices.

In conventional practice, a plasma is usually accompanied by an energetic electron beam, and the plasma is commonly contaminated with varying amounts of neutral gas particles. Collision processes of the neutral gas particles and other attendant phenomenon seriously alter the behavior of the plasma and may render such a plasma unfit for various uses. In conventional practice a plasma may be generated by electron bombardment of gas molecules as in an arc discharge such as disclosed in the application of John S. Luce, Serial No. 833,897, filed August 14, 1959, now Patent No. 2,956,195, issued October 11, 1960. However, the discharge of this application and other similar discharges are not free of objectionable neutral gas particles. Still another characteristic of these prior discharges is that the voltage applied between widely spaced electrodes to produce the discharges causes contaminants from the electrodes to be introduced into the discharges and also causes electric fields within the discharges, particularly along the discharge, thus resulting in certain instabilities therein. In addition, use of widely spaced electrodes in these prior discharges resulted in the necessity for providing very special baffles and differential pumping means to insure stability of the discharges.

With a knowledge of the limitations of prior devices in the production of a plasma, it is a primary object of this invention to provide an ion gun for production of a well defined, relatively uncontaminated plasma.

It is another object of this invention to provide an ion gun for production of a plasma that is characterized by very little extraneous electrical fields, particularly longitudinal electric fields along the plasma.

It is still another object of this invention to provide an ion gun for production of a plasma that requires no special baffles or differential pumping means, and in which very little electrode material is introduced into the plasma during operation of the ion gun.

These and other objects and advantages of this invention will become apparent upon consideration of the following detailed specification and the accompanying drawings wherein:

FIG. 1 is a cross sectional view of a preferred embodiment of the invention, and

FIG. 2 is a cross sectional view of a mirror type machine utilizing the device of FIG. 1.

The above objects have been accomplished in the present invention by providing an evacuated system in which there is contained an ion gun for producing a plasma and a region where the plasma is to be utilized. The ion gun comprises an anode and a cathode mounted in concentric relationship with a narrow annulus therebetween. The facing surfaces of the rear portions of the anode and cathode are recessed to form an annular manifold. Positioned within this manifold is an annular intermediate electrode aligned with the annulus between the anode and cathode. Gas is fed to the manifold and an arc discharge is established between the anode and cathode. A pressure differential is established along the annulus by the evacuated system and a uniform magnetic field is established so that the field lines traverse and are parallel to

2

the annulus. The gas fed to the manifold is withdrawn therefrom into the annulus between the anode and cathode by the pressure differential thereacross and is substantially ionized by the arc discharge across the annulus.

5 It has been determined that the plasma produced by the apparatus of this invention will attain a reasonable density and stability when the immediate electrode is aligned with the annulus, for any given rate of gas feed and magnetic field strength. The existence and positioning of the intermediate electrode is a critical feature of the present invention. Little, if any, plasma is produced when this electrode is omitted. Furthermore, when this electrode extends into the outer (radial) portion of the manifold so that the annulus between the cathode and anode is not shadowed, the resultant plasma is small and extremely unstable. Thus, a satisfactory plasma can be obtained only when the intermediate electrode is essentially aligned with the annulus or is recessed into the inner portion of the manifold. The thus formed plasma is withdrawn from the annulus by the combined effects of the pressure differential and the magnetic field.

The ion gun of this invention is considered suitable for providing a plasma to be utilized in a variety of devices characteristically similar in that a plasma, i.e., an electrically neutral mixture of ions and electrons, is employed therein for sundry purposes. Electrically neutral plasmas are of interest in the thermonuclear fields and for experimental purposes; while charged ion beams, which may be produced by charge separation and/or charged particle acceleration treatment of neutral plasmas, may be used in charged particle accelerators, mass spectrometers and the like.

It is one aspect of this invention to utilize the ion gun in a magnetic mirror type thermonuclear machine. When so used, the ion gun is positioned at about center of one of the magnetic mirror regions to assure as uniform a magnetic field as possible in the manifold and annulus regions of the ion gun. The resultant hollow plasma will follow the field lines and will terminate against some form of baffle placed in or near the second magnetic mirror region. This plasma may then be used as a means for the breakup of molecular ions causing atomic ions to be formed and magnetically trapped within the hollow plasma, the plasma wall acting as a shield for the trapped atomic ions against the instreaming of neutral particles from the walls of the machine, in a manner similar to that set forth in the application of John S. Luce, Serial No. 833,897, filed August 14, 1959, entitled, "Hollow Carbon Arc Discharge," now Patent No. 2,956,195, issued October 11, 1960.

50 In FIG. 1, one embodiment of the subject device is shown. An anode electrode 1 and a cathode electrode 2 are mounted in concentric relationship with a narrow annulus 3 therebetween. The anode 1 is mounted on a conducting electrode support 4 which, in turn, is mounted on the end of a support tube 5. Tube 5 is insulatingly supported in one end wall of the housing 20. Cathode 2 is mounted directly upon the end of a second support tube 6 which, in turn, is insulatingly supported in the rear portions of the anode and cathode are recessed to form an annular manifold 7. Positioned within this manifold 7 is an intermediate cylindrical electrode 8 which is mounted on a conducting electrode support 9. This support 9, in turn, is mounted upon the end of a third support tube 10. This tube 10 is insulatingly supported in the one end wall of housing 20. An exact spacing of this intermediate electrode 8 with respect to the anode 1 and cathode 2 is accomplished by the insertion of an annular insulator 11 between support tube 10 and support tube 5, and the concentric annular insulator 12 between support tube 6 and the electrode support 9. A gas-tight seal be-

tween these components is provided by the insertion of O-rings or similar seals 13 therebetween. The manner in which the electrodes are supported, as discussed above, is not limited to the specific means set forth, since any other conventional means may be employed for this purpose.

Electrode support 4 is provided with an axial passageway in which a tube 14 is disposed. This passageway communicates with an axial passageway 15 in anode 1. Passageway 15, in turn, communicates with radial passageways 16 in anode 1. Feed gas, such as hydrogen or deuterium, for example, is fed from a gas supply 21, through tube 14, passageways 15 and 16 into the manifold 7.

The housing 20 forms a chamber 29 which is evacuated by means of a vacuum pump, not shown, connected to a member 22 communicating with the chamber 29. Tube 6, which supports cathode 2, is connected by an electrical lead 28 to the negative terminal of a variable D.C. supply 27. Tube 5, which is electrically connected to anode 1, is connected by lead 24, switch 25, and lead 26 to the positive terminal of supply 27. The negative terminal of the supply 27 is grounded, as shown.

A uniform magnetic field is provided by a concentric electromagnetic coil 23 disposed around the housing 20. Coil 23 is energized by a source of D.C. potential, not shown. The magnetic field lines provided by this electromagnet are in axial alignment with the annulus 3 between the cathode 2 and anode 1.

A baffle 17 is disposed in confronting relation to the electrodes of the ion gun and is mounted on the other end of housing 20 by an insulator 18. Baffle 17 may be grounded by a lead 19, and a switch 76, if desired.

Some of the dimensions and materials of construction of the device of FIG. 1 are given below, by way of examples. The length of the anode and cathode is 2½ in.; diameter of anode is 1¼ in.; thickness of annulus 3 is $\frac{1}{16}$ in.; effective length of anode and cathode is 1 in.; outside diameter of cathode is 2 in.; effective length of intermediate electrode 8 is 1¼ in.; thickness of intermediate electrode is $\frac{1}{16}$ in.; inside diameter of manifold 7 is $\frac{3}{4}$ in.; and outside diameter of manifold 7 is 1¾ in. The electrodes 1, 2 and 8 are machined from graphite stock, and the electrode supports and support tubes are copper. Steatite is used as the insulating material for members 11 and 12. The outside diameter of the intermediate electrode 8 is 1¼ in., so that the outer surface thereof is aligned with the inner surface of the annulus 3.

The above dimensions and materials of construction, with the exception of the position of the intermediate electrode, are not critical to the operation of the device of FIG. 1. For example, the electrodes may be constructed from stainless steel, the insulating members may be constructed from any of conventional inert insulating materials, and the dimensions of the electrodes and the annulus therebetween may be made larger or smaller with substantially the same operating results if operating parameters are modified accordingly.

In a normal operation of the device of FIG. 1, the ion gun is aligned in a uniform magnetic field, for example 3000 gauss, so that field lines traverse and are parallel to, the annulus 3. The region external to the ion gun in the chamber 29 is evacuated to about 8×10^{-5} mm. Hg or less. The pressure in the manifold 7 is at a higher value than in chamber 29 during the time the device is producing a plasma. Gas is admitted to the manifold 7 from gas supply 21 through passageways 14, 15, 16. With the intermediate electrode 8 electrically floating, a voltage is applied between the anode 1 and cathode 2 by means of supply 27, and when this voltage reaches about 800 volts, a gas discharge is struck between these electrodes. The discharge can be initiated at lower voltages when the magnetic field is higher. The voltage is then raised to an operating value of about 1800 volts. The current flow between the anode and cathode is then about 0.2 ampere for the spacing and pressure cited above.

Immediately upon striking the discharge, an ion plasma is formed along the magnetic field lines within and external to the ion gun. There is a pressure differential across the annulus 3 by virtue of the difference in pressures between the manifold 7 and the chamber 29. The gas drawn through this annulus by this pressure differential is substantially ionized by the arc discharge between the anode and cathode. The plasma thus emerging from the ion gun is relatively uncontaminated by neutral particles. The plasma will follow the field lines until it strikes the electrode or baffle 17. The baffle 17 may be used as a reflecting electrode for the plasma which strikes it when the switch 76 is opened, or alternately it may be used as a collector electrode for the plasma when the switch 76 is closed. With a magnetic field strength of 3000 gauss and a voltage of 1800 volts between the anode and cathode, a plasma of about 3×10^{11} particles/cc. is obtained. With a fixed rate of gas feed and a fixed applied voltage, this plasma density has been shown to vary nearly proportionally to the square of the magnetic field strength.

The plasma of ions produced in the operation of the above-described device does not have any applied axial potential gradient therealong. The absence of such an applied potential gradient substantially eliminates extraneous electrical fields, particularly longitudinal fields. Thus, it can be seen that the plasma of ions produced by the device described above does not have certain of the objectionable electrical fields which are characteristic of conventional gas-fed arc discharges of the prior art. By positioning all the electrodes at one end of the device, less electrode material gets into the plasma as contaminant, and such positioning materially reduces baffling and differential pumping problems that are characteristic of prior art arc discharges.

It should be noted here that with the small current of 0.2 ampere between the electrodes that there will be a minimum of electrode heating and at this small current flow there will be less problem of the electrodes disintegrating because of a lack of heat due to the small current flow between the electrodes. The device of this invention may be operated at higher voltages and currents, and when so operated, cooling means for the electrodes may be required. When required, cooling coils would be mounted on the electrode supports.

It should be noted here, in the event the plasma generator is used in an apparatus such as an accelerator or the like, that the housing 20 may be eliminated and an evacuated region of such apparatus may provide the hereinbefore-mentioned means providing an evacuated system.

The principles of the ion gun discussed above may be used in a mirror type machine such as disclosed in the embodiment of FIG. 2. A similar type of mirror machine is described in U. S. Patent No. 2,920,234, issued January 5, 1960, to John S. Luce, entitled, "Device and Method for Producing a High Intensity Arc Discharge." In FIG. 2 of said patent the ion gun is positioned in one of the magnetic mirror regions such that the magnetic field lines traverse the annulus between the anode and cathode and are substantially parallel with this annulus. The mirror machine of FIG. 2 of the present application comprises an inner chamber 59 and two end chambers 60 and 61. The inner chamber 59 is connected through an opening 63 to a vacuum pump, not shown. The inner chamber 59 is enclosed by means of a liner 65. The liner 65 may be constructed from stainless steel or Inconel, for example. The inner chamber 59 is enclosed with an outer enclosure 30. Enclosure 30 is provided with an opening 62 in communication with one of the end chambers 60, and is provided with an opening 64 in communication with the other end chamber 61. Openings 62, 64 are connected to separate vacuum pumps, not shown, for evacuating chambers 60 and 61, respectively. Disposed in one end of enclosure 30 is an ion gun assembly consisting of an anode 31, and a cathode 32, defining an annulus 33 therebetween. Cathode 32 is supported by

an annular tubular member 36. The anode 31 is supported by the annular tubular member 35. Disposed within a manifold 37 between the anode and cathode is an intermediate electrode 38. This electrode 38 is connected to a concentric tubular member 40. Disposed about the tubular member 36 of the ion gun assembly is an annular section of insulating material 73 which supports the concentric tubular members of the gun assembly and extends through the one end of the enclosure 30.

Gas is supplied to the manifold 37 of the ion gun from a gas source 51, through a tube 44, and then through passageways in the anode 31. The members 35, 40 and 36 are disposed in concentric relation with respect to each other and are held in a suitable spaced relation with respect to each other by insulating means in the same manner as in the device of FIG. 1. Member 36, which is electrically connected to the cathode 32, is connected to a source of D.C. supply 57 by a lead 58. The other side of D.C. supply 57 is connected by a lead 56 to the member 35, which is in electrical contact with the anode 31. The D.C. supply 57 is a variable D.C. supply for supplying operating voltage between the cathode and anode. The anode, cathode, and intermediate electrode of the ion gun are positioned in the center of a magnetic mirror region provided by an annular electromagnetic coil 66. Disposed between coil 66 and the ion gun assembly are a plurality of baffles 67 disposed about the ion gun assembly. These baffles 67 are insulatingly mounted on a portion of the inner chamber wall 65. A second annular electromagnetic mirror coil 66' is provided at the other end of the device and is mounted in concentric relation to a baffle or plate 47. This plate 47 is grounded through a plate support member 74, lead 49, and switch 75. The coils 66 and 66' are energized by a source of D.C. potential, not shown. The member 74 is encompassed or surrounded with an insulating material 48 which extends through the other end of the enclosure 30. Disposed between the annular electromagnetic coil 66' and the plate 47 are a plurality of annular baffles 68. These baffles 68 are insulatingly mounted on an extension of the inner liner 65.

In the operation of the device of FIG. 2, the arc discharge is established in an identical manner to that described above for FIG. 1. After the arc discharge has been established between the anode 31 and cathode 32, the pressure differential across the annulus 33 between the manifold 37 and the inner chamber 59 is such as to cause the gas within the manifold 37 to flow through the annulus 33 and thus through the arc discharge. The collimating effect of the magnetic field lines within the annulus 33 plus the pressure differential across the annulus 33 will cause a plasma of relative uncontaminated ions to be ejected from the ion gun in the form of a hollow beam 72. This beam 72 will follow the magnetic field lines provided by the mirror coils 66 and 66', and any other coils that may be provided therebetween. This beam 72 will follow the magnetic field lines until it strikes the plate 47. As in the device of FIG. 1, the magnetic field strength is about 3000 gauss, the voltage across the electrode at operating value is about 1800 volts, and a plasma of about 3×10^{11} particles/cc. is obtainable. As in the device of FIG. 1, the plasma beam 72 of FIG. 2 is substantially free of neutral gas particles because of the fact that the gas is substantially ionized by the arc discharge in the annulus 33 before it leaves the ion gun.

This plasma beam 72 may be used as a dissociating mechanism in the same manner as set forth in the aforementioned Patent No. 2,956,195. When the plasma as shown in FIG. 2 is used as a dissociating mechanism, a stream 71 of molecular ions are injected from an ion source through an accelerator 70 into the inside wall of the plasma 72 in an operating zone between the mirror coils. A portion of the molecular ions 71, when they come in contact with the plasma beam 72, are dissociated by this plasma beam into atomic ions and neutrals. The

atomic ions will be magnetically trapped due to the effect of the confining magnetic field and will form a ring of atomic ions. This trapping principle is fully set forth in the co-pending application of John S. Luce, Serial No. 5 728,754, filed April 15, 1958. The portion of the molecular ions that are not dissociated by the plasma beam 72 will continue to move in the same trajectory they had before contacting the beam 72. The neutrals formed in the dissociating process will flow off at a tangent to the points of dissociation and are lost to the system. These neutrals, however, may be used as an input to a particle accelerator, if desired. It should be noted that all electrical potentials for the device of FIG. 2 are applied in a zone removed from the operating zone of the plasma between the mirror coils, thus preventing formation of a longitudinal electrical field along the plasma beam 72. Absence of this field will insure better stability of the plasma beam.

The plasma beam 72 of FIG. 2 is considered to be 10 superior to the hollow carbon arc discharge of the aforementioned Patent No. 2,956,195, for the reason that the plasma 72 is essentially free of neutral gas particles, and therefore, when used as a dissociating mechanism, will not introduce extraneous matter or neutral particles into 15 the plasma of atomic ions formed in the dissociating process. As discussed above for the device of FIG. 1, the device of FIG. 2 will produce a plasma with less contaminants from electrode materials than plasmas produced by prior arc discharges. Also, there are less baffling 20 and differential pumping problems with the device of FIG. 2 than there are for prior arc discharges. In addition, there are less electric fields produced in FIG. 2 than in prior arc discharges. As pointed out above, the plasma beam 72 will serve as a means for preventing the 25 in-streaming of neutral particles from the walls of the machine, in a manner similar to that set forth in the aforementioned Patent No. 2,956,195.

The gas supplied to the ion gun of FIG. 2 may be hydrogen, for example, deuterium, tritium, or mixtures 30 thereof. The pressure in chamber 59 is maintained at a value of about 3×10^{-5} mm. Hg, and the pressure in the end chambers 60 and 61 is maintained at a value of about 1×10^{-4} mm. Hg, for example. For some applications, lower pressures may be desirable.

45 The accelerator tube 70, referred to above, is energized by a suitable high voltage generator. The beam 71 of molecular ions may be D_2^+ or D_3^+ , for example, and are injected from the source 69 and through the accelerator 70 with an energy of about 600 kev.

50 Essentially all low energy neutral particles that strike the plasma beam 72 are immediately ionized by the plasma and are pumped out of the system along the plasma beam and through the space between either the baffles 67 and the ion gun or between the baffles 68 and 55 baffle 47 into the end chambers.

The plasmas supplied by the ion gun of both FIG. 1 and FIG. 2 are different from conventional arc discharges in that they are relatively quiescent and stable under their 60 normal operation conditions. Conventional gas-arc discharges may be and are usually highly contaminated by neutral gas particles fed to the arc discharge. This is a disadvantage when they are used as dissociating mechanisms, for the reason that these neutral particles will interfere with the build up of a sufficiently dense plasma 65 of atomic ions to the necessary density to provide a thermonuclear plasma. It should thus be seen that the plasma beam of FIG. 2 is a more efficient dissociating mechanism because of its characteristic of being relatively 70 free from objectionable neutral gas particles and electrode contaminants therein.

This invention has been described by way of illustration rather than limitation, and it should be apparent that the invention is equally applicable in fields other than those described.

What is claimed is:

1. An improved ion gun comprising a container, an ion gun assembly disposed in one end of said container, said ion gun assembly comprising an anode and a cathode mounted in concentric relationship with a narrow annulus therebetween, an anode support member connected to said anode and mounted in one end of said container, a cathode support member mounted to said cathode and disposed in said one end of said container, the rear portions of said anode and cathode being recessed to form an annular manifold, an intermediate electrode positioned within said manifold, a support member connected to said intermediate electrode and extending into said one end of said container, means for insulatingly supporting said support members in concentric relation with respect to each other, means for insulating said support members from said one end of said container, a source of gas supply, a gas supply feed tube connected to said gas source and extending through said member supporting said anode, an axial passageway within said anode connected to radial passageways within said anode, said radial passageway communicating with said manifold, said gas feed tube being in communication with the said axial passageway within said anode, a source of variable D.C. voltage, means for connecting said D.C. source between said anode and said cathode, means connected to and in communication with said container for evacuating said container, a baffle mounted to the other end of said enclosure in confronting relation with the face of said ion gun assembly, an electromagnetic coil disposed in concentric relation around said enclosure, said electromagnetic coil supplying a magnetic field, the magnetic field lines of said coil being substantially parallel to and in alignment with the annulus between said cathode and said anode, said coil extending from an area adjacent to the electrodes of said ion gun assembly to an area encompassing said baffle, said intermediate electrode within said manifold being aligned with the annulus between said anode and said cathode, the pressure within said container providing a pressure differential across said annulus, whereby the arc discharge established between said anode and said cathode by said variable D.C. supply substantially ionizes the gas flowing through said annulus by virtue of said pressure differential to provide a plasma beam substantially free of neutral gas particles.

2. The ion gun set forth in claim 1, wherein the magnetic field strength is about 3000 gauss, the region adjacent to the face of the electrodes of the ion gun is evacuated to about 8×10^{-5} mm. Hg, the gas supplied to said manifold from said gas source is hydrogen, the voltage applied between the anode and cathode is about 1800 volts, said intermediate electrode being electrically floating, and the current flow between the anode and cathode being about 0.2 ampere, whereby said plasma beam provided by said ion gun has a density of about 3×10^{-11} particles/cc.

3. An improved ion gun comprising a container, means connected to said container for evacuating said container, an ion gun assembly disposed in one end of said container, said ion gun assembly comprising an anode and a concentrically disposed cathode defining an annulus between said anode and said cathode, the rear portions

of said anode and said cathode defining a recessed manifold, an intermediate electrode positioned within said manifold and aligned with said annulus, a source of feed gas, means for feeding gas from said source into the interior of said manifold at a controlled rate, means connected to said anode, said cathode, and said intermediate electrode for supporting them, said supporting means being mounted within one end of said container, means for providing a containing magnetic field within said container to provide magnetic field lines that are parallel to and in alignment with the annulus between said anode and said cathode, a source of variable D.C. supply, means for connecting said D.C. supply across said anode and said cathode to supply operating voltage thereto, the pressure within said container providing a pressure differential across said annulus, whereby the arc discharge established across said anode and said cathode by said D.C. supply will substantially ionize the gas supplied to said annulus from said manifold, said gas being directed to said annulus by virtue of said pressure differential across said annulus, said ion gun assembly thereby providing a substantially ionized plasma which is collimated by said magnetic field to supply a substantially cylindrical hollow plasma to the evacuated region of said container.

4. The device set forth in claim 3 wherein the container is provided with a central chamber and two end chambers, said ion gun assembly electrodes being positioned in one end of said central chamber, a baffle disposed in the other end of the central chamber, said magnetic field being provided by a pair of electromagnetic mirror coils, one of said mirror coils being disposed in concentric relation to the electrodes of said ion gun assembly, the other mirror coil being disposed in concentric relation to said baffle, said evacuating means being connected to each of said respective central chamber and said end chambers.

5. The device set forth in claim 4 wherein the central chamber is evacuated to a pressure of about 3×10^{-5} mm. Hg, the voltage across said anode and said cathode is about 1800 volts, the gas fed to the said manifold is hydrogen, the magnetic field strength supplied by said magnetic mirror coils is about 3000 gauss, said end chambers being maintained at a pressure of about 1×10^{-4} mm. Hg, whereby the plasma ejected from said ion gun assembly is substantially free from neutral gas particles, said plasma following the magnetic field lines provided by said mirror coils until said plasma contacts said baffle.

6. The device set forth in claim 5 and further including a source of molecular ions, means for accelerating a beam of molecular ions from said ion source into the inside wall region of said plasma at an angle substantially perpendicular to said plasma, said plasma partially dissociating said beam of molecular ions into atomic ions, neutral particles, and electrons, said atomic ions being magnetically trapped within the area defined by said plasma, and said neutrals being ejected away from said plasma.
